UNITED STATES PATENT OFFICE.

GEORGIA ANNIE LAMAR, OF TUCUMCARI, TERRITORY OF NEW MEXICO.

WASHBOILER.

995,158.

Specification of Letters Patent. Patented June 13, 1911.

Application filed February 25, 1911. Serial No. 610,783.

To all whom it may concern:

Be it known that I, GEORGIA ANNIE LAMAR, a citizen of the United States, residing at Tucumcari, in the county of Quay and 5 Territory of New Mexico, have invented certain new and useful Improvements in Wash-boilers, of which the following is a specification, reference being had to the accompanying drawings.

10 This invention relates to improvements in wash boilers and has for its object to provide a wash boiler of simple and novel construction whereby the necessity for rubbing the articles to be washed to remove the dirt 15 therefrom is eliminated.

A further object of the invention is to provide means removably arranged within the boiler shell for directing a plurality of jets of boiling water and steam upon the 20 clothes with sufficient force to cause the water to thoroughly penetrate the clothes whereby the same are quickly cleansed without requiring manual labor.

A still further object of the invention is 25 to provide a wash boiler of the above character, the parts of which may be easily and quickly assembled and may be readily arranged in a boiler of the common construction, the device being extremely efficient in 30 practical use and of small cost to manufacture.

With the above and other objects in view, the invention consists of the novel features 35 of construction, combination and arrangement of parts hereinafter fully described and claimed, and illustrated in the accompanying drawings, in which—

Figure 1 is a vertical longitudinal section of a wash boiler embodying my improvements; Fig. 2 is a top plan view thereof; Fig. 3 is a section taken on the line 3—3 of Fig. 1; and Fig. 4 is a bottom plan view of the removable false bottom.

Referring in detail to the drawings 5 45 designates a boiler shell which may be of any desired form and is constructed of tin or galvanized sheet metal.

My improved washing device is adapted 50 to be arranged within the boiler shell and comprises a false bottom 6 which consists of the plate 7 of substantially the same shape in plan as the bottom of the boiler and which is disposed in spaced parallel relation thereto when in its operative position. 55 The false bottom plate 7 is supported by means of the vertical wall 8 which is pro-

vided with a flange 9 at one edge over which the edge of the bottom plate 7 engages, said plate being bent upon itself and clamped upon the flange 9 as shown at 10 to rigidly 60 secure the plate 7 and wall 8 together. The other edge of the wall 8 which rests upon the bottom of the boiler shell is formed with a bead 11 by bending said edge over the wire 12. It will be observed from reference 65 to Fig. 1 that when properly positioned within the boiler, the edge of the false bottom plate 7 is spaced from the inner wall of the boiler shell, thus permitting the water to enter beneath the plate 7 through a plurality of openings 13 which are provided in each end of the vertical wall 8. The bottom plate 7 is further supported upon the bottom of the boiler by means of a plurality of members 14 which are substantially V- 70 shape in cross sectional form and are arranged transversely upon said plate. The longitudinal edges of these members are provided with suitable attaching flanges 15 to be riveted or otherwise securely fixed to 75 the plate 7.

The false bottom plate 7 is provided at its longitudinal edges adjacent to each end thereof and at opposite points with the openings 16 to receive the ends of the short tubes 17 which are provided with attaching flanges 18 to be bent against the under side of the false bottom plate 7 and riveted thereto. These tubes 17 may be of any desired cross 80 sectional form but are preferably of the 85 form shown in Fig. 1 and gradually taper from their lower to their upper ends. The smaller upper ends of the tube 17 are telescopically engaged in the lower ends of the water conducting tubes 19 which also taper 90 longitudinally and are slightly curved and laterally extended at their upper ends as indicated at 20. The spaced vertical tubes 19 on each side of the boiler are connected 95 at their upper ends by means of the horizontal plate 21 which is preferably formed integral therewith. From reference to Fig. 3 it will be observed that the tubes 19 are inclined transversely of the boiler and have 100 their upper connected ends closely engaged with the inner face of the boiler shell.

In order to prevent the accidental removal of the tubes 19 from the upper ends of the short tubes 17, when removing articles from the boiler, I provide the device shown in 110 Fig. 2 which consists of a casting 22 secured to the connecting plate 21 which extends be-

tween the opposed ends of the tubes 19, by means of a plurality of rivets 23. Screws 24 having finger plates or wings 25 extend through the boiler shell and have threaded engagement in the casting 22. Washers 26 are also integrally formed upon the outer ends of the screws 24 for engagement with the shell 5. It will be obvious that the upper ends of the tubes 19 may be held in close engagement with the shell by adjusting the screws 24 to bind the connecting plate 21 against the inner face of the shell.

The upper laterally extended ends of the conducting tubes 19 have suitably secured thereto the discharge spouts 27. Two of these spouts communicate with each of the tubes 19 and are arranged in spaced relation and they are gradually reduced in diameter to provide the outlets 28 which are eccentrically disposed with relation to the opposite end of the spouts which are connected to the tube 19. It will be observed, by reference to Fig. 1 that the outlets 28 of each pair of discharge spouts 27 are oppositely disposed, or in other words, said outlets are adapted to direct the boiling water and steam to the right and to the left of the respective discharge spouts, thus distributing the same over the greater portion of the clothes which are in the boiler, and thoroughly agitating or churning the water and causing the same to permeate the articles being washed and thus remove the dirt therefrom. It will be readily seen, that owing to the fact that the boiling water strikes upon the inclined annular wall 29 of the discharge spouts, it will be directed with great force from the contracted outlets 28 in a downward direction into the boiler.

In the use of my improved wash boiler, the false bottom member 6 is arranged upon the bottom of the boiler shell, and the upper ends of the tubes 19 secured to the sides of the boiler as previously described. The water and particles of soap or washing powder are then placed in the boiler together with the articles to be washed. When the water comes to a boil, it gradually rises through the tubes 17 and 19, the steam forcing the boiling water with considerable pressure upon the annular walls 29 of the discharge spouts and through the outlets 28 thereof. A steady stream of boiling water and steam is in this manner discharged at a number of places upon the articles being washed. The said articles are in this manner thoroughly agitated in the boiling soapy water and the water forced through the different fabrics whereby the same are very quickly and thoroughly cleansed. After the lapse of the proper length of time, the articles are removed from the boiler and replaced by others. When no longer desired for use, the screws 24 are removed and the false bottom member 6 together with the

connected tubes 17 and 19 are bodily removed from the boiler and stored away until again desired for use.

While I have shown and described the preferred construction and arrangement of my improved washing device, it will be understood that the same is susceptible of considerable modification without departing from the essential features or sacrificing any of the advantages thereof. It will also be observed that by means of the device constructed as above set forth, whereby steam and water are being constantly discharged upon the contents of the boiler, all liability of the same boiling over is eliminated, so that the user does not have to exercise constant watchfulness as is required in the use of a boiler of the common construction.

Having thus described the invention what is claimed is:—

1. The combination with a boiler, of a false bottom arranged therein consisting of a body plate and a vertical wall rigidly secured to said plate at its edge and resting upon the bottom of the boiler, said wall having a plurality of openings therein, short transverse supporting members rigidly fixed to the under side of said bottom plate to support the same in spaced relation to the bottom of the boiler, vertical tubes rigidly secured to said bottom plate at each of its longitudinal edges and extending therethrough, conducting tubes telescopically engaged upon said vertical tubes, plates integrally connecting the latter tubes at their upper ends upon each side of the boiler, means extending through the boiler shell and said plates to rigidly secure the tubes thereto, and a plurality of discharge spouts in the upper end of each of said conducting tubes.

2. The combination with a boiler, of a false bottom arranged therein, a pair of short vertical tubes secured to said false bottom adjacent to each of its longitudinal edges and opening beneath the same, conducting tubes telescopically engaged upon the upper ends of said short tubes, said conducting tubes on each side of the boiler being integrally connected at their upper ends to castings, screws disposed through the boiler shell and threaded into said castings to rigidly secure the upper ends of the conducting tubes thereto, and a plurality of discharge spouts in the upper end of each of said tubes.

3. The combination with a boiler, of a false bottom arranged therein consisting of a plate arranged in parallel relation to the bottom of the boiler shell, and a vertical wall rigidly secured to said plate at one edge and resting at its other edge upon the bottom of the shell, a plurality of supporting members transversely arranged upon the under side of the plate, said plate having

openings adjacent to each end and at each side thereof, short vertical tubes extending above said openings and rigidly secured to said bottom plate, the vertical wall of said 5 false bottom having a plurality of openings therein, said wall being disposed in spaced relation to the boiler shell, conducting tubes telescopicallv engaged upon the upper ends of said short tubes, said tubes being curved 10 and gradually tapered at their upper ends, the extremities of said tubes at their upper ends being laterally extended toward each

other and rigidly connected together, and a plurality of discharge spouts arranged in the upper end of each tube, the adjacent 15 spouts having their outlets disposed in opposite directions to discharge the water downwardly into the boiler.

In testimony whereof I hereunto affix my signature in the presence of two witnesses. 20

GEORGIA ANNIE LAMAR.
